UNITED STATES PATENT OFFICE.

GEORGE HERBERT SCOTT, OF BECKENHAM, ENGLAND.

MOORING MAST AND MOORING GEAR FOR AIRSHIPS.

Application filed August 22, 1921. Serial No. 434,167.

To all whom it may concern:

Be it known that I, GEORGE HERBERT SCOTT, a subject of the King of Great Britain, residing in Beckenham, Kent, England, have invented certain new and useful Improvements in Mooring Masts and Mooring Gear for Airships, of which the following is a specification.

This invention relates to mooring masts and their associated gear for airships of the kind in which a mooring fitting on the bow of the ship is coupled to a resiliently mounted mooring fitting on the mast head with the aid of a mooring cable.

According to the present invention the airship is moored to a fitting carried by a swinging arm mounted at the top of the masthead, and this fitting and the arm are so supported that the fitting has complete azimuthal freedom and is capable of assuming any inclination, within limits, in any vertical plane.

The invention will be more particularly described with reference to the accompanying drawings, wherein Fig. 1 is an elevation partly in section of the upper end of a mooring mast constructed in accordance with the invention; Fig. 2 is a vertical section of the mast fitting shewing the application of a detail hereinafter referred to; Fig. 3 is a plan view of the platform at the top of the mast shewing one form of centring arrangement for the tilting lever.

The mast 1 is of lattice structure and carries at its upper end a steel plate pedestal 2 the upper part of which is conical and which is surrounded at its base by a circular platform 3. The latter may be reached from the ground by means of a ladder inside the mast and a short external ladder connects it with a lower platform secured to the lattice structure. The upper part of the pedestal is fitted with a pair of gymbal rings 4, 5 the inner one of which supports at an intermediate point a steel telescopic tube 6, 7 which is normally kept extended by means of a series of strong helical springs 8 fitted inside the tube. Spring-urged latches 9 engage a collar at the lower end of the inner tube 7 to prevent the latter being forced out of the outer tube by the springs 8, while permitting it to be telescoped within the outer tube. The tube 6, 7 can be restored to the vertical po-

sition, when displaced therefrom, by means of four wire ropes 10 attached to eyes 11 on the lower end of the tube inside the pedestal 2. These ropes pass around a series of sheaves 12 and rollers 13 and terminate in a single eye 14 to which the hook of a differential pulley block 15 is attached. The other hook of the block is secured to the mast so that by hauling on the working chain 16 all four centring wires 10 can be tightened simultaneously to bring the tube, 6, 7 into the vertical position, or can be slackened off to permit the inclination of the tube.

The upper end of the tube 7 has fitted to it a bell-mouthed conical cup 17 formed with a flange at its lower end which is bolted to a corresponding flange on a tube 18 mounted to rotate freely on ball thrust bearings 19 and radial bearings 20 fitted in the tube 7. The conical masthead fitting 17 cooperates with the fitting carried on the nose of the airship, which comprises a short horizontal outrigger 21 which is adapted to turn about a longitudinal axis on the ship and to which is hinged a male cone 22 having a taper corresponding with that of the conical cup of the masthead fitting. The outrigger 21 is also provided with a sheave 23 over which a wire rope 24 passes from the airship down through the axis of the cone 22. By means of this rope the cone on the airship is drawn into the cup on the masthead fitting in the operation of mooring, after attachment of the hauling-in rope. When an airship is to be moored a considerable length of the hauling-in rope is paid out and brought down to the ground and laid out to leeward of the mast, towards which side also the tilting telescopic tube is inclined. When the air ship has reached the approximate mooring position the wire rope is let down from the nose fitting and attached to the hauling-in rope by a suitable coupling device. The airship then rises by discharge of ballast, lifting the rope from the ground, and is then hauled down by winding in the hauling-in rope until the cone 22 is pulled right home into the cup 17, in which position it is held by spring-urged latches 25 fitted in the walls of the cup. The shock of engagement of cone and cup, or the liability to damage due to overwinding is met by the telescopic character of the tilting tube 6, 7, resulting merely

in the compression of the springs 8 within the tube. The hauling in is continued, preferably by hand gear, until the inner tube 7 is telescoped into the outer tube 6 to such an extent that the latches 9 engage behind the collar 26 towards the upper end of the inner tube 7. The tube is then brought into the vertical position by the centring wires 10 and fixed in this position as by bars 27 adjusted between the lower end of the tube 7 and the base of the pedestal 2. The airship fitting 22 being secured by the latches 25, the hauling-in rope can be disconnected and the wire rope belonging to the ship's equipment drawn up into the vessel. Another wire rope 28 (Fig. 2), which is attached to the nose of the ship by means of a small bridle, is then passed down through the conical fittings 22, 17 and telescopic tube 6, 7 and attached to the mast structure by an extension screw or turnbuckle device 29, shewn in the lower part of Fig. 1. To release the ship from the mast the pressure on the latches 25 is relieved by tightening up the turnbuckle 29, leaving the ship temporarily secured by the releasing pendant 28 which, when the pilot is ready to start, is freed, as for example by knocking back a slip link 29^a on a shackle connecting the turnbuckle 29 with the rope. When the ship is clear the tube is extended by withdrawing the spring latches 9, the upward movement of the inner tube being controlled by means of a steel plate fitting 30 (Fig. 2) which is placed in the cup 17 and a rope passed through the tube, 6, 7 to the winding gear below.

It will be understood that the precise construction hereinbefore described may be departed from in many respects without exceeding the scope of the present invention. For example, instead of depending on the tension on the mooring cable for exerting automatically a righting couple on the tilting lever, for which purpose the cable is led between rollers vertically under the centre of support of the lever, a resilient erecting device may be applied to the lower end of the lever so as to constrain the tilting thereof and when tilted apply a restoring couple.

To facilitate engagement of the ship and masthead fitting cones, the female cone may be made of a wider angle than the other.

Having thus described the nature of my said invention and the best means I know of carrying the same into practical effect I claim:—

1. Apparatus for mooring airships comprising a mooring mast, an arm or lever mounted thereon with freedom to tilt in any vertical plane, a mooring fitting on the said arm, and a mooring fitting on the airship adapted to be coupled with the mooring fitting on the arm.

2. An apparatus according to claim 1,

wherein the engaging fittings are in the form of a male cone on the airship and a female cone on the tilting lever, or conversely.

3. An apparatus according to claim 1, wherein the tilting lever has a telescopic construction and is normally extended by the action of springs or equivalent mechanism.

4. An apparatus according to claim 3 wherein the lever is telescoped for mooring purposes by winding up the hauling-in cable and is secured by spring-urged latches.

5. An apparatus according to claim 1, wherein the tilting lever is provided with means whereby it can be centred or erected when the ship is moored.

6. An apparatus according to claim 2, wherein the male and female cones are provided with coupling devices adapted to hold the fittings coupled after the hauling-in cable is cast off.

7. An apparatus according to claim 1, wherein the masthead mooring fitting is movable axially upon the tilting lever and also rotatable about the axis thereof.

8. An apparatus according to claim 1, wherein the ship mooring fitting is mounted to swing in two planes at right angles to each other.

9. In an apparatus for mooring airships, the combination of supporting means, longitudinally adjustable means mounted on the said supporting means having a coupling member, a coupling member forming a universal joint attached to the nose of the airship, and means for drawing said coupling members into engagement with each other.

10. In an apparatus for mooring airships, supporting means, a telescopic boom pivotally mounted thereon and having a locking coupling member, a coupling member for attachment to the nose of an airship adapted to engage and be locked in the locking coupling member and means for drawing the coupling members into engagement with each other.

11. In an apparatus for mooring airships, a substantially cone-shaped coupling member for attachment to the nose of an airship and having a universal joint, a coupling member mounted on telescopic means and having a substantially cone-shaped socket and locking means for locking the cone-shaped coupling member therein, a swivel post on which said cone-shaped socket member is mounted, supporting means for said post and means for drawing the said coupling members into engagement with each other.

12. In an apparatus for mooring airships, the combination of a supporting means, a telescopic boom mounted on said supporting means, a locking-box upon the end of said boom, a coupling member attached by a universal joint and swivel to the nose of the airship, and a flexible member passing

through the axial line of said boom, locking-box and coupling member between the airship and the mooring mast.

13. In an apparatus for mooring airships,
5 supporting means, a telescopically yielding
shock absorbing boom pivotally mounted
thereon and having a locking coupling mem-
ber, a coupling member for attachment to
the nose of an airship adapted to engage

and be locked in the locking coupling mem- 10
ber and means for drawing the coupling
members into engagement with each other.

In testimony whereof I have signed my
name to this specification.

GEORGE HERBERT SCOTT.
